(57) **CLAIM**

The ornamental design for a lockable container, as shown and described.

DESCRIPTION

FIG. 1 is a front exploded perspective view of a lockable container showing our new design;

FIG. 2 is a rear exploded perspective view thereof;

FIG. 3 is a front perspective view thereof;

FIG. 4 is a left side perspective view thereof, the right side perspective view being a mirror image thereof;

FIG. 5 is a rear perspective view thereof; and,

FIG. 6 is a top perspective view thereof.

The broken lines shown in the drawings represent portions of the lockable container that form no part of the claimed design.

1 Claim, 6 Drawing Sheets
